UNITED STATES PATENT OFFICE.

GEORGE H. RUMKE, OF DENVER, COLORADO.

AMUSEMENT DEVICE.

1,200,032.

Specification of Letters Patent.

Patented Oct. 3, 1916.

Application filed January 4, 1916. Serial No. 70,221.

To all whom it may concern:

Be it known that I, GEORGE H. RUMKE, a citizen of the United States, residing at Denver, in the county of Denver and State 5 of Colorado, have invented certain new and useful Improvements in Amusement Devices, of which the following is a specification.

This invention relates to new and useful 10 improvements in amusement devices of the type commonly known as motordromes, its object being to provide in association with suitable operating mechanism, an annular motordrome which is pivotally mounted to 15 be moved about a determinate axis out of the plane in which it is normally disposed.

A motordrome thus constructed is as a means for affording entertainment, a decided improvement over the stationary 20 dromes at present in use, since it permits of raising the endless riding surface along which a vehicle is being driven, to any angle from the horizontal to the perpendicular without interrupting the performance.

25 With the above object in view, my invention consists in the features of construction and arrangement of parts shown in the accompanying drawings in the various views of which like parts are similarly designated, 30 and in which,

Figure 1 is a sectional view of my improved motordrome, Figs. 2, 3, 4 and 5 similar views showing motordromes of modified construction, and Fig. 6, a plan view of the 35 construction shown in Fig. 1.

Referring first to Fig. 1 of the drawings, the motordrome consists of an annular trackway 2 made in any desired manner and of any suitable material which interiorly 40 has a riding surface 3. The riding surface extends transversely at substantially right angles to the horizontal, and a supplemental inwardly inclined riding surface 4 of reduced width adjoins the main riding surface 45 at its lower edge to provide an approach along which a vehicle driven within the trackway may gradually ascend. The annular trackway is normally supported upon a level foundation 5 and is hinged as at 6 to 50 be moved through an arc of approximately ninety degrees. A bail 7 applied adjacent the upper edge of the trackway at points opposite to that at which it is hinged, is attached to a pull-rope 8 which running 55 over an elevated sheave 9, is at its opposite end either connected with a windlass or

other winding mechanism, or fastened to a stationary anchor.

In the operation of the motordrome, a vehicle is driven at a constantly increasing 60 velocity along the floor upon which the trackway is supported and onto the approach 4 across which it gradually ascends in a spiral course onto the main riding surface 3 along which the vehicle continues to 65 move in a substantially horizontal plane. At this stage in the performance, the trackway is slowly moved about its pivotal axis by a pull exerted on the rope 8, until its main riding surface is positioned transversely at right angles to the perpendicular. The vehicle now moves in an upright 70 endless course to which it is held by centrifugal force, and it continues performing this extraordinary feat until the annular trackway is again lowered to its normal horizontal 75 position when the vehicle may gradually descend onto the approach and across the same onto the floor upon which the drome is supported.

In the form of my invention shown in Fig. 1, the annular trackway is open at the top and bottom so that when it is moved to an upright position, the performance may be observed from opposite sides of the same. 80

In the form illustrated in Fig. 2, the trackway forms an integral part of a floor 12 and the performance can in consequence be seen only through the open top of the structure. 85

In the construction shown in Fig. 3, an approach 13 is formed integrally upon the floor upon which the trackway is supported, and the transversely straight driving surface is raised to the vertical position separate from the tapering supplemental surface which remains permanently in a horizontal position. 90

In the construction illustrated in Figs. 4 and 5 the approach has been omitted and the annular trackway has a single endless driving surface directly adjoining the horizontal floor upon which it is normally supported. In the form shown in Fig. 4, this runway is transversely straight, while in 100 the modification illustrated in Fig. 5, it is transversely concave. A track of this character is particularly adapted for motorcycles which can be driven onto the upright surface without the aid of a tapering approach such as is used in the first-described 105 preferred form of my invention. 110

Having thus described the construction and operation of my improved motordrome, I desire it understood that any suitable means for the pivotal support of the annular trackway or for moving the same through a determinate arc, may be used within the spirit of my invention as set forth in the appended claims.

I claim:

- 10 1. In a motordrome, a trackway having a riding surface and an inclined approach, said trackway being movably mounted for effecting a pivotal movement of said surface about a determinate axis.
- 15 2. In a motordrome, the combination with a surface, of a trackway having a riding-surface, and an inclined approach between said surfaces, the said trackway being pivotally mounted for moving said riding-surface to a position at an angle to the other surfaces.
- 20 3. The combination with a supporting surface, of a motordrome composed of an annular body provided with an internal

riding surface, normally supported upon the first-mentioned surface and mounted for movement about a horizontal axis fixed with relation to the same.

4. The combination with a supporting surface, of a motordrome composed of an annular body provided with an internal riding surface, and mounted for movement about a horizontal axis fixed with relation to the same.

5. The combination with a supporting surface, of a motordrome comprising an annular body having an internal riding surface which from the line along which it adjoins the first mentioned surface extends in a substantially straight line at right angles to the same.

In testimony whereof I have affixed my signature in presence of two witnesses.

GEORGE H. RUMKE.
